[54] COIN-OPERATED AUTO RACE AMUSEMENT DEVICE

[75] Inventor: Richard A. Nunis, Laguna Beach, Calif.

[73] Assignee: Walt Disney Productions, Burbank, Calif.

[] Term: 14 Years

[21] Appl. No.: 839,284

[22] Filed: Oct. 3, 1977

[51] Int. Cl. D21-01

[52] U.S. Cl. D21-01

[58] Field of Search.....D34/5CC, 5R, 5L; D19/63; 273/86B; 35/11R; 46/255

[56] References Cited

U.S. PATENT DOCUMENTS

D.188,376 7/1960 Hotkins et al. D34/5CC

3,339,307 9/1967 Floyd et al. D19/63

Primary Examiner—Melvin B. Feifer
Attorney, Agent or Firm—Fulivider, Patton, Rieber, Lee
& Utecht

CLAIM

The ornamental design for a coin-operated auto race amusement device, substantially as shown and described.

DESCRIPTION

FIG. 1 is a front view of a coin-operated auto race amusement device showing my new design the side opposite that shown in FIG. 1 is plain and unornamental; and

FIG. 2 is a side elevational view of said device, the side opposite that shown being identical.

FIG. 1
FIG. 2